UNITED STATES PATENT OFFICE.

LORRAINE J. PITKIN, OF CHICAGO, ILLINOIS.

DESIGN FOR A BADGE.

SPECIFICATION forming part of Design No. 22,038, dated December 6, 1892.

Application filed August 13, 1890. Serial No. 361,937. Term of patent 14 years.

To all whom it may concern:

Be it known, that I, LORRAINE J. PITKIN a citizen of the United States residing at Chicago in the county of Cook and State of Illinois have invented certain new and original Design for Badge, of which the following is a specification.

My invention consists in a novel design for a badge, and badge pendant.

10 The leading features of my design for a badge are: first, a five pointed star having a central circle inclosing a group of figures, each point of the star bearing a figure hereinafter specified, and the points having between them segmental sections bearing respectively, the letters F,—A,—T,—A,—L; and secondly, a bar bearing the letters O,—E,—S.

15 The complete badge is represented in the annexed drawing, but the pendant or star-shaped portion thereof may, under some circumstances, be used apart from the bar and ribbon shown.

20 The badge consists of a bar A, which may be provided with a pin or other fastening device; a ribbon, B, attached to and hanging from the bar, and a five pointed star C, suspended from the bar through the medium of the ribbon B. The bar bears the letters O, E, and S. The ribbon is in five colors, arranged in the following order, beginning at the left: blue, yellow, white, green, and red. The pendant, C, is, as above mentioned, in the shape of a five-pointed star, the central 25 portion of which bears a circular rim or border, a, inclosing a group, b, of five figures. The central figure is represented with a crown upon her head. The first figure to the left of the central figure is represented with a timbrel in her hand. The figure to the extreme left is represented in a kneeling position with culms of barley in her hands. The first figure to the right of the center is represented with a cup in her right hand, and the figure to the extreme right is represented 30 in a kneeling position with hands clasped and elevated.

45 The points of the star, which are formed

with raised borders or lines, bear symbols or representations as follows: the first point to the right of the center, sword and veil raised; the second point to the right of the center, a sheaf of wheat; the third or lowest point, a crown and scepter; the fourth point, or the lower point on the left of the center, a broken column; and the fifth or upper left hand point a cup. Between the points of the star are segmental sections, c, having raised borders, and bearing the letters F,—A,—T,—A,—L,—the letter F occupying a space at the center or between the highest two points, and the other letters occupying the spaces following in order to the right. These segmental portions are shown with raised radial lines.

65

The bar, the ribbon, and the star or pendant constitute the complete badge, and will ordinarily be used together, but the star may be worn separately if desired. The ribbon is usually made of silk, and the bar or pendant of suitable metal or alloy. As shown, the bar A is formed with a rectangular body having a raised rim or border and a central enlargement of circular outline, also having a raised border, with a small scroll at the meeting point of the upper edge of the bar and the circular enlargement, the bar being without other ornament or projection.

70

Having thus described my invention, what I claim is—

80

1. A design for a badge, consisting of a star with a central group of figures, and bearing in its respective points the figures of a sword and veil, a sheaf of wheat, a crown and scepter, a broken column, and a cup; segmental sections between the points of the star bearing respectively the letters F,—A,—T,—A,—L; a ribbon by which the star is suspended; and a bar at the upper end of the ribbon, bearing the letters O,—E,—S,—substantially as shown.

85

2. In a design for a badge, a star with a central group of figures, and having in its respective points figures of a sword and veil, a sheaf of wheat, a crown and scepter, a broken column, and a cup; and segmental

90

95

sections between the points of the star bearing respectively the letters F,—A,—T,—
A,—L.

3. In a design for a badge, a bar having a
5 rectangular body and a circular central en-
largement, both with raised rims, scrolls at
the meeting points of the raised rims and
the upper side of the bar, and letters O,—

E,—S,—upon the face of the bar, substan-
tially as shown.

In witness whereof I hereunto set my hand
in the presence of two witnesses.

LORRAINE J. PITKIN.
